United States Patent Office

Des. 186,290

Patented Oct. 6, 1959

186,290

FASTENER INSERTING TOOL

Richard W. Hitchcock, Boston, and Wallace A. Underwood, Manchester, Mass., assignors to United Shoe Machinery Corporation, Flemington, N.J., a corporation of New Jersey

Application May 26, 1959, Serial No. 56,066

Term of patent 14 years

(Cl. D54—13)

Fig. 1

Fig. 1 is a perspective view of a fastener inserting tool embodying my new design;

Fig. 2 is a left side elevation of the tool;

Fig. 3 is a right side elevation of the tool;

Fig. 4 is a top plan view of the tool; and

Fig. 5 is a bottom plan view of the tool.

We claim:

The ornamental design for a fastener inserting tool, substantially as shown.
